(57) **CLAIM**

The ornamental design for “a portion of a navigation/player tracking/payment panel for a gambling unit,” as shown and described.

DESCRIPTION

The FIGURE is a front view of a portion of a navigation/player tracking/payment panel for a gambling unit.

The dashed lines shown in the FIGURE represent environmental structure and form no part of the claimed design. The dotted lines shown in the FIGURE represent the borders between claimed subject matter and unclaimed subject matter and form no part of the claimed design.
